(57) **CLAIM**

The ornamental design for an ear canal spray nozzle assembly, as shown and described.

DESCRIPTION

FIG. 1 is a perspective view of an ear canal spray nozzle assembly.

FIG. 2 is a left side view of the ear canal spray nozzle assembly of FIG. 1.

FIG. 3 is a right side view of the ear canal spray nozzle assembly of FIG. 1.

FIG. 4 is a front view of the ear canal spray nozzle assembly of FIG. 1.

FIG. 5 is a rear view of the ear canal spray nozzle assembly of FIG. 1.

FIG. 6 is a top view of the ear canal spray nozzle assembly of FIG. 1.

FIG. 7 is a bottom view of the ear canal spray nozzle assembly of FIG. 1; and,

FIG. 8 is a top view of the ear canal spray nozzle assembly of FIG. 1 shown without the bottle for clarity of illustration of the bottle neck clip.

The dot dash broken line showing immediately adjacent the shaded form is included for the purpose of illustrating the bounds of the claimed design, while all other broken lines illustrate environmental structure and form no part of the claimed design.
